UNITED STATES PATENT OFFICE.

CHARLES H. READ, OF PITTSBURGH, PENNSYLVANIA.

SLACK TAKE-UP AND BRAKE-RELEASE MECHANISM.

Application filed June 15, 1922. Serial No. 568,473.

To all whom it may concern:

Be it known that I, CHARLES H. READ, a citizen of the United States, residing at Pittsburgh, in the county of Allegheny and 5 State of Pennsylvania, have invented a new and useful Improvement in Slack Take-Up and Brake-Release Mechanism, of which improvement the following is a specification.

My invention relates to improvements in 10 the foundation brake rigging of railway vehicles. The objects of the invention are to produce an apparatus of this kind in which the traverse or movement of the levers in applying the brakes is increased without 15 increasing the present normal travel of the piston with a consequent conservation in air pressure and a quicker brake application than is possible with the apparatus now in use and in which a quick and positive brake- 20 shoe release is obtained.

I accomplish these objects by means of the apparatus hereinafter more fully described, which broadly stated comprises two sets or 25 systems of levers designated herein as the primary set and the secondary set, and relatively occupying the same vertical plane. The secondary set being operated by and deriving its power from the primary set and 30 acting or operating simultaneously with the primary set or system and in the same direction and in such manner as to increase or enlarge the scope or action of the primary system without increasing the present normal piston travel. The said apparatus or 35 device is hereinafter more fully described, reference being had to the accompanying drawings forming part hereof, in which:

Fig. 1 is a diagrammatic plan view of the air brake cylinder, its levers and the slack 40 adjustment and brake-shoe release.

Fig. 2 is a conventional diagrammatic view of the ordinary foundation brake rigging, the structure being shown in plan except the wheels, which are shown in elevation.

Referring to said drawings: 1 is an air 45 brake cylinder, 2 and 3 are respectively the operating levers, herein called the primary levers, or more commonly called the live and dead levers, and which for convenience I will herein call the live and dead levers respectively; the said live lever is pivotally connected to and directly operated by the piston rod 4, which is operatively seated in 50 said cylinder, the said dead lever 3, being

pivotedly connected to a stationary point, or as shown in the drawings, to the end of the cylinder opposite the live lever 2. A connecting element comprising two independent connecting rods 5 and 5' is interposed between said levers, the main or longest section 5 being connected at one end to the dead lever, and the opposite end pivotally to a lever 6, herein called the secondary lever, which is disposed between said primary levers 2 and 3; the section 5' of said connecting element is connected at one end to the live lever and at the opposite end to said lever 6 at or near the outer end thereof. An auxiliary connecting rod 7 is 60 connected at one end to the live lever at a point between the short connecting rod 5' and the pivotal point of connection between the piston and the live lever 2, and at the opposite end with the lever 6 at or near 65 the inner end thereof. 8 is a rod connected to the lever 6 at or near the end thereof, the opposite end of said rod being connected to a plate 9, between which and the plate 10 a compressive spring 11 is operatively 70 mounted on the link or clevis 12, to one end of which the said plate 10 is connected, the opposite end of said link or clevis being connected to a rod 13 which is pivotally 75 connected to the dead lever. The said plates 9 and 10 are slidably mounted on said link whereby when a brake application is made the movement of the piston carries the live lever forward, which in turn carries the inner end of the secondary lever 6 forward, 80 thereby compressing said spring, the retraction of which upon the release of air pressure produce a quick and positive release of the brake-shoes.

The operation of the device is as follows: 85 In order to make a brake application, the piston of the cylinder is caused to move in the usual manner, carrying the live lever connected to the outer end of said piston into the position shown by dotted lines, and 90 through the agency of the connecting element, the dead lever is brought into the position shown by the dotted lines. The outer ends of said levers, which from their function I define as the primary levers, being, 95 as shown, moved inward or toward each other, applying the brake-shoes in the usual manner. It will be noted that the adjacent ends of the two independent rods 5 and 5', which constitute the connecting ele- 100 105 110

ment which is pivotally secured to the lever 6, disposed between the operating levers 2 and 3 are compelled to move in opposite direction during brake application, the end of 5 the short section moving toward the dead lever and the end of the long section moving toward the live lever, thus shortening the combined length of the two sections and carrying the outer end of the two operating 10 levers 2 and 3, herein called the dead and live levers, closer together with a shorter running travel of the piston rod than can be obtained in the operation of the foundation rigging now in use, in which the connecting 15 rod is formed of a single continuous element. The effect of this difference is that the brakes can be applied in a shorter period of time with a shorter running travel of the piston and a consequent saving of 20 brake pressure and consumption of air. The movement of the piston operating levers 2 and 3 in a brake application compresses the spring, as heretofore herein described, and as a matter of course utilizes 25 a portion of the cylinder air pressure in so doing, the comparatively short running travel of the piston, however, lessens air pressure reduction in the cylinder and the gain in this respect more than compensates 30 for the power used in compressing the spring. When the brakes are released in the usual manner, the retraction of the spring quickly and positively releases the brake-shoes from the wheels and draws back 35 the entire rigging and places the apparatus in full release position.

In Fig. 2, I show a conventional diagrammatic view of the ordinary foundation brake rigging, in which a continuous one piece connecting rod is used. As this construction is 40 well known, a brief statement of the parts will suffice; *a* is the brake cylinder; *b* and *c* are respectively the live and dead levers; *d* is the connecting rod connecting said levers, the lower end of said levers being connected with the brake-shoe levers.

I do not wish or intend to limit myself 50 to any particular mechanical means of producing the simultaneous augmentation of the action of the levers, as it is obvious that other mechanical means may be so employed; my intention being, however, to cover broadly the dual action of the primary and secondary system of levers, one 55 of which, the secondary system, derives its power from the primary system and augments the movement or action of the primary system in a brake application.

The "slack" which it is necessary to "adjust" or take up, arises from wear of pins and holes, wear of brasses, loose boxes in pedestals, etc., and it is provided for in the ordinary brake foundation rigging by increasing the travel of the piston, but as now 65 arranged this increased piston travel leads

to a loss of air pressure in the brake cylinder, greater consumption of air, slower 70 brake application, etc. The present invention meets and remedies these disadvantages by shortening the piston travel, while increasing the travel of the entire rigging.

It will be noted that heretofore the slack was taken up and held positively and permanently until released by some other action and through some other instrumentality 75 than the brake release. In the present invention the slack is taken up and upon release of the brakes automatically assumes its normal condition.

Having described my invention, what I 80 claim and desire to secure by Letters Patent is:

1. A slack take up and brake release mechanism for railway vehicles, comprising a plurality of sets of levers, including a 85 primary set and a secondary set in the same vertical plane, and means cooperating with said levers for automatically releasing the slack at each brake release.

2. A slack take up and brake release 90 mechanism for railway vehicles comprising an actuating set of levers and an actuated set of levers and means cooperating with said actuated set adapted to increase the movement of the actuating set without 95 increasing the travel of the piston.

3. A slack take up and brake release mechanism for railway vehicles comprising primary and secondary systems of levers and an element connecting said systems including a divided rod, the secondary set of levers being adapted on brake application to shorten said connecting rod and to 100 lengthen the same on brake release.

4. A slack take up and brake release 105 mechanism for railway vehicles, comprising a plurality of sets of levers, including an actuating set and an actuated set and means interposed between said sets of levers and cooperating with the actuating set 110 of levers to simultaneously operate both sets in the same direction and increase the movement of the actuating set without increasing the travel of the piston.

5. A slack take up and brake release 115 mechanism for railway vehicles, comprising a primary and a secondary set of levers, a connecting element divided into two parts, the said parts being arranged on different 120 horizontal planes.

6. In the foundation brake rigging of railway vehicles, a connecting element comprising a plurality of rods, the adjacent ends of which are pivotally secured upon a common support disposed between the live and dead levers.

7. In the foundation brake rigging of railway vehicles, a lever disposed between the operating levers and a connecting element comprising a plurality of rods, the 125 130

inner ends of which are pivotally secured to said lever, and the outer ends respectively to the live and dead levers respectively.

8. In the foundation brake rigging of railway vehicles, the combination of an air pressure cylinder, a piston operable therein, a dead lever pivotally connected to one end of said cylinder, a live lever connected to the piston of said cylinder, a connecting rod comprising two independent sections, a lever disposed between the dead and live levers, the inner end of the short section of said connecting rod being connected to one end of said lever and at the opposite 10 end to the live lever, the inner end of the main section of said connecting rod being connected to said lever and the opposite end to the dead lever.

9. In a slack take up and brake release mechanism comprising a plurality of sets of levers, a connecting rod interposed between said levers formed in two sections, the said sections being so arranged that on brake application their combined length 25 between said levers is shortened and their combined length being limited to the original distance between said levers when the apparatus is in released position.

10. In the foundation brake rigging of railway vehicles, the combination of slack take up and brake-shoe release mechanism, including a connecting rod formed in two sections, a lever disposed between the ex-

treme outer ends of said sections, the inner ends of both of said sections being pivotally secured upon said lever and the outer ends of said sections being pivotally secured to the dead and live levers respectively, in combination with means to quickly and positively release the brake-shoes upon the 40 release of brake pressure.

11. In the foundation brake rigging of railway vehicles, the combination of a brake cylinder, operating levers, the inner end of one of which is pivotally secured to the 45 piston of said cylinder and the corresponding end of the other is pivotally secured to a stationary point at the opposite end of said cylinder, slack take up and brake release mechanism including a connecting rod 50 formed in two sections, a lever interposed between the operating levers, the inner ends of both of said sections of said connecting element being pivotally secured to said lever and the opposite ends of said sections being pivotally secured to the operating levers respectively, an auxiliary connecting rod pivotally secured to the lever connected to the piston and at the opposite end to said lever, and a compressive spring mounted 55 between the inner end of said lever and the dead lever.

In testimony whereof, I have hereunto signed my name.

CHARLES H. READ.
